SHIP PROPULSION

Romeo Cote, Providence, R. I.

Application June 30, 1945, Serial No. 602,529

5 Claims. (Cl. 115—49)

1

My present invention relates to boats, and more particularly to a novel type of ship propulsion.

The principal object of the present invention is to provide a means of ship propulsion which will not be dependent on a single, central source of power.

Another object of the present invention is to provide a means of ship propulsion which will produce a considerable saving of power over the conventional screw propeller.

A further object of the present invention is to provide a means of ship propulsion which is easier and more economical to manufacture and install than the conventional screw propeller.

Another object of the present invention is to provide a ship propulsion system which can readily be adjusted or repaired without interfering with the progress of the ship.

With the above and other objects and advantageous features in view, my invention consists of a novel arrangement of parts, more fully described hereinafter, in conjunction with the accompanying drawing, and more particularly claimed in the appended claims.

In the drawing:

Fig. 1 is a plan view, partially diagrammatic, of a ship equipped with the propulsion system of the present invention;

Fig. 2 is a side elevation of one of the propulsion units;

Fig. 3 is a rear edge view of the same; and

Fig. 4 is a view similar to Fig. 2, half of the casing being removed.

The conventional screw propeller ship propulsion is accompanied by certain recognized disadvantages which the art has been unable to overcome. The screw is driven by a single large power plant which takes up valuable cargo space and makes the ship highly vulnerable in a single spot. A disabled engine in time of war or peace means a crippled ship brought to a dead stop. Repairs are usually difficult at sea. Furthermore, the initial installation is slow and costly, the setting of the main shaft requiring the highest degree of accuracy. The screw propeller requires more power than its predecessor, the paddle wheel, because it does not drive as directly. The old side wheel steamers developed unusual speed with relatively small power.

The present invention is designed to eliminate the aforementioned disadvantages by utilizing the principle of the paddle wheel in a novel type of ship propulsion system.

Referring more in detail to the drawing illustrating my invention, the ship 10 (Fig. 1) is pro-

2

vided with a plurality of paddle wheel driving units 11, preferably arranged in tandem as shown. Each pair of units is independently driven by any suitable conventional power means 12 (dotted lines) such as steam, Diesel, gasoline, or electric, the source of power being immaterial.

Each driving unit 11 comprises an integral one-piece housing 13 of generally inverted U-shape (Figs. 2 and 4) with flattened sides 14, a straight 10 front end 15, and angularly disposed rear end 16. The sides 14 are provided with vertical slots 17 (Fig. 4) oppositely disposed. The paddle wheel 18, housed in the housing 13, is mounted on a shaft 19 of sufficient length to extend through the 15 slots 17. Thus the shaft 19 and paddle wheel 18 may be moved vertically in the slots 17 to raise or lower the paddle wheel 18 as desired. To seal the housing 13, the shaft 19 passes through doors 20 which are slidably mounted in channels 21 (Fig. 2) to cover the slots 17 in any position of the shaft.

The shaft and paddle wheel are adjustably retained in position by journaling the shaft 19 in bearings or collars 22 conventionally packed to 25 seal the housing. Threaded rods 23 are rotatably mounted in the collars 22 and extend upwardly through threaded openings in tabs 24 extending laterally from the upper side portions of the casting (Fig. 3). The top of the rods 23 are squared, as at 25, so that turning movement of the rods by 30 means of a wrench or similar tool will raise or lower the shaft. The shaft 19 is connected to the power means 12 through a universal joint 26 (Fig. 3).

35 In installing or operating the unit 11, the bottom of the ship 10 is provided with an opening 27. The opening 27 may be sealed by a door 28 which is slidable horizontally as by means of the gear and crank arrangement 29 (Fig. 3). The 40 unit 11 is bolted to the deck over the opening, the housing 13 having a sealed cut-out portion permitted movement of the door 28. After the door is withdrawn, the rods 23 are turned until the paddle wheel 18 is sufficiently immersed in the 45 water to drive the ship. To prevent the water from rising too high in the housing 13, the air in the housing may be maintained at a pressure of approximately four pounds by any conventional compressing means (not shown) and fed 50 to the housing 13 through the connection 30.

The advantages of the above described construction are obvious. If any particular unit is disabled, it can be raised and repaired without cutting off the other power units or stopping the ship. Furthermore, the units are simple in con-

struction, easy to install, economical to operate, and save considerable cargo space. It should be further noted that in a heavy sea, the conventional screw drive is often lifted clear of the water thus wasting its power. By the system of the present invention, some units of the system will always be immersed and driving in any position of the ship.

While I have described a specific constructional embodiment of my invention, it is obvious that changes may readily be made in the size, shape, and relative arrangement of the parts without departing from the spirit and scope of the invention as defined in the appended claims.

I claim:

1. A device for propelling ships comprising a housing having an open bottom and positioned over an opening in the bottom of a ship, a shaft mounted in said housing and extending through the sides thereof, a paddle wheel in said housing mounted on said shaft, means for vertically adjusting the height of said shaft and paddle wheel in said housing, means for closing the opening in the bottom of the ship when the shaft and paddle wheel are in raised position, and power means for rotating said shaft and paddle wheel.

2. A device for propelling ships comprising a housing having an open bottom and positioned over an opening in the bottom of a ship, a shaft mounted in said housing and extending through the sides thereof, a paddle wheel in said housing mounted on said shaft, means for vertically adjusting the height of said shaft and paddle wheel in said housing, means for supplying air under pressure into said housing and power means for rotating said shaft and paddle wheel.

3. A device for propelling ships comprising a housing having an open bottom and positioned over an opening in the bottom of a ship, a shaft

mounted in said housing and extending through the sides thereof, a paddle wheel in said housing mounted on said shaft, means for vertically adjusting the height of said shaft and paddle wheel in said housing, means for closing the opening in the bottom of the ship when the shaft and paddle wheel are in raised position, means for supplying air under pressure into said housing, and power means for rotating said shaft and paddle wheel.

4. A device for propelling ships comprising a housing having an open bottom and positioned over an opening in the bottom of a ship, said housing having vertically disposed slots in opposite sides thereof, a cover slidably mounted on each side and adapted to seal said slots, a shaft in said housing extending through said slots and cover, the ends of said shaft being journaled in vertically adjustable bearings, a paddle wheel in said housing mounted on said shaft, means for closing the opening in the ship when said shaft and paddle wheel are in raised position, and power means for rotating said shaft.

5. A device for propelling ships comprising a housing having an open bottom and positioned over an opening in the bottom of a ship, said housing having vertically disposed slots in opposite sides thereof, a cover slidably mounted on each side and adapted to seal said slots, a shaft in said housing extending through said slots and cover, the ends of said shaft being journaled in vertically adjustable bearings, a paddle wheel in said housing mounted on said shaft, means for closing the opening in the ship when said shaft and paddle wheel are in raised position, means for supplying air under pressure into said housing, and power means for rotating said shaft.

ROMEO COTE.
